UNITED STATES PATENT OFFICE.

EZRA C. BROCKWAY, OF TRENTON, NEW JERSEY, ASSIGNOR TO MERCHANTS CO-
OPERATIVE CO., OF TRENTON, NEW JERSEY, A CORPORATION OF NEW JERSEY.

CLOCK-BANK.

1,091,422.

Specification of Letters Patent. Patented Mar. 24, 1914.

Application filed April 15, 1913. Serial No. 761,383.

To all whom it may concern:

Be it known that I, EZRA C. BROCKWAY, a citizen of the United States, residing at Trenton, in the county of Mercer and State 5 of New Jersey, have invented certain new and useful Improvements in Clock-Banks; and I do hereby declare the following to be a full, clear, and exact description of the invention, such as will enable others skilled 10 in the art to which it appertains to make and use the same.

This invention relates to coin controlled winding mechanism for clocks and the like, and as its principal object contemplates the 15 provision of a winding mechanism so constructed that the time piece can not be rewound except by the introduction of a coin.

A further object is to construct the device in such manner that after the introduction 20 of the coin and the subsequent winding of the clock, the withdrawal of the winding key will effect the delivery of the coin into a till or coin receiver arranged within the casing of the clock.

25 A still further object of this invention is to construct the winding mechanism with such regard to proportion, number and arrangement of parts that it may be cheaply manufactured, readily applied to any clock 30 or time piece of standard construction, and will be durable and efficient in its operation.

The above and additional objects are accomplished by such means as are illustrated in the accompanying drawings, described in 35 the following specification, and then more particularly pointed out in the claim which is appended hereto and forms a part of this application.

With reference to the drawings, wherein 40 I have illustrated the preferred embodiment of my invention as it is reduced to practice, and throughout the several views of which similar reference numerals designate corresponding parts: Figure 1 is a rear elevation 45 of a clock equipped with this invention, illustrating several of the various parts in broken away section to clearly disclose the interior arrangement of the mechanism. Fig. 2 is a section on the line 2—2 of Fig. 1.

50 Fig. 3 is a detail view of the device employed in preventing the withdrawal of the coin from the box after it has been inserted. Fig. 4 is a section on the line 4—4 of Fig. 1; and Fig. 5 is a detail view of the coin cup. 55 Proceeding now to the description of the

drawings, the numeral 1 designates the clock casing, the rear wall of which is provided, as at 2, with an elongated horizontally extending coin slot, the middle portion of which is enlarged to produce a circular opening 3, adapted to permit the insertion of the shank 4 of the winding key 5. This winding key 5 differs from the ordinary winding key employed in time pieces in this respect, that the terminal of the shank 4 is 60 bifurcated to produce the fork tines 6, the inner faces of which are spaced apart a distance slightly less than the thickness of a dime, which is the coin preferably employed in this mechanism. It will be readily apparent that by this arrangement of the tines 6, the resiliency of the metal of which the member 5 is constructed will act to grip the coin in the desired position.

In order to permit the application of the 75 coin to the main spring stem 7, there has been provided a cup-shaped member 8 which may be formed integrally with or secured to the member 7 in any desired manner. This cup member 8, the mouth of which opposes 80 the rear wall 9 of the clock, is provided internally with a plurality of laterally extending inwardly directed tongues 10 which are formed integrally with the member 8 and are substantially V-shaped. The 85 tongues 10 are arranged in the nature of ratchets with the corresponding edges similarly inclined so that the inserted coin may not be rotated to turn the main spring abnormally. In this connection it will be 90 readily observed that if the main spring is turned positively the coin will engage the straight edges of the members 10 and rotate the stem 7 in a normal direction, but if an attempt is made to rotate the stem abnormally the coin will slide over the inclined edges of the tongues. It will be observed 95 that by placing the coin between the tines 6 of the key and inserting it through the slot 2, that the coin will be projected into the 100 cup 8 and will engage the straight edges of the tongues 10. To wind the clock it then remains only to turn the key 5 in the usual manner.

Since the principal object of this invention is to prevent the withdrawal of the coin after the winding of the main spring, it is necessary to provide some automatic means for engaging the coin and effecting its delivery into the till or receiving chamber, as 110

indicated at 11 in Fig. 1. There has, therefore, been provided in this invention a hinged plate 12 mounted interiorly of the clock casing and on the rear wall 9 thereof. 5 The plate 12 is bifurcated, as illustrated in Fig. 3, to produce the yoke arms 13 and is disposed on the wall 9 so that the yoke arms in normal position lie one on each side of the opening 3 and extend across the slot 2. 10 From the foregoing it will be noted that as the coin is inserted the plate 12 will be swung upwardly on its hinge until the coin has reached the cup 8, at which time the rotation of the key 5 will tend to bring the 15 coin in a vertical position, thus bringing the arms 13 on each side of the coin, and permitting the plate 12 to swing downwardly into its normal position. After the completion of the winding operation, the key is 20 withdrawn in the usual manner, but the coin is held against withdrawal by the plate 12, as will be readily apparent by reference to the drawing. As the tines 6 issue from the 25 opening 3 they will of course withdraw from the coin, which will then drop into the till or receiver 11.

The actual construction and operation of this device being thus disclosed, it now remains to emphasize the fact that the simplicity of the construction and arrangement of the various parts of this invention is regarded as the essential feature of the device. 30

In reduction to practice, I have found that the form of my invention, illustrated in the drawings and referred to in the above description, as the preferred embodiment, is the most efficient and practical; yet realizing that the conditions concurrent with the

adoption of my device will necessarily vary, 40 I desire to emphasize the fact that various minor changes in details of construction, proportion and arrangement of parts may be resorted to, when required, without sacrificing any of the advantages of my invention, as defined in the appended claim. 45

What is claimed is:

A clock bank including a clock casing, a clock mechanism arranged therein, a coin cup carried by the main spring stem, said cup being provided interiorly with diametrically extending coin grooves, an elongated horizontally extending coin slot formed in the rear wall of said clock casing and in alinement with the main spring stem, a 55 hinged plate mounted interiorly of said casing and on the rear wall thereof, yoke arms formed on said plate and normally disposed to extend across the said coin slot, said rear wall of said casing being provided approximately midway the length of the said coin slot with a central opening adapted to receive a winding key, said opening being formed in registration with the space between the said yoke arms, a winding key, a pair of spring tines formed terminally of the said winding key and adapted to hold a coin, said hinged plate being adapted to permit the insertion of the coin and key and to permit the withdrawal of said key but being 60 further adapted to prevent the withdrawal of said coin. 65

In testimony whereof I affix my signature in presence of two witnesses.

EZRA C. BROCKWAY.
